UNITED STATES PATENT OFFICE.

FRANK PARDEE, OF HAZLETON, PENNSYLVANIA.

SPRAL CHUTE.

1,256,724.

Specification of Letters Patent. Patented Feb. 19, 1918.

Application filed June 10, 1915. Serial No. 38,383.

To all whom it may concern:

Be it known that I, FRANK PARDEE, a citizen of the United States, and resident of the city of Hazleton, county of Luzerne, 5 and State of Pennsylvania, have invented certain new and useful improvements in Spiral Chutes, of which the following is a specification, reference being had to the accompanying drawings.

10 The invention relates more especially to chutes used for conveying coal or other substances from a higher to a lower level, the object being to diminish or prevent breakage during the passage. In the use 15 of chutes for lowering coal from the screens and cleaners in breakers to the pockets or bins, as well as in chutes for other purposes such as the lowering of ice, fractures and chipping takes place, and in time the loss 20 thus caused amounts to large sums. Various efforts have been made to prevent such losses by the peculiar construction of conveyers or chutes of one kind and another, but generally with indifferent success.

25 The invention consists of a spiral chute composed of helical floor-plates with an incline or pitch toward the axis and a downward pitch, said floor-plates having an upturned or curved flange at the outer and 30 inner periphery, the structure and floor-plates being suitably supported and arranged with connecting parts as hereinafter more fully described and claimed.

In the drawings Figure 1. is an elevation 35 of the spiral or conveyer and shows an inlet at the top and another inlet somewhat lower down. Fig. 2, is a top plan of the same and Fig. 3, an underside plan thereof. Fig. 4, is a detail elevation of a quarter-turn of the 40 spiral and floor plates, and Fig. 5, is a plan thereof. Fig. 6, is a detail of part of the lower floor plate which is shortened and modified to leave space at the outlet for a connecting discharge or leading-off chute. 45 Fig. 7, shows a modified form of plate with an integral outer flange and Fig. 8, a lower half-length plate without an outer flange.

In practice the spiral conveyer is preferably constructed around a central post A, 50 which acts as a main support for the whole structure. The post A, is provided with a series of rods a, a, having an upward incline from the post. The rods a have an upturned outer end a', a', to which an outer spiral band B, is secured by bolts b, b, and the band B has a sufficient vertical or flaring

rise to form a wall which prevents the coal or other substance from escaping or being thrown over the outer edge. As shown the band B, is vertical, or nearly so, which is 60 regarded as the preferable formation.

The floor-plates C, are segmental and helical in form and occupy the space between the band B and the post A, such plates being secured to the rods a by bolts c. The 65 floor-plates C, form sections of from one-eighth to one-half of a complete spiral turn. They are arranged to overlap at their edges, the lower edge of each plate being above the upper edge of the next lower plate. The 70 floor-plates C, are formed from plate metal, and those which compose the structure from the inlet to the outlet have integral outer and inner upturned peripheral flanges c', and c², the flange c', being made to bear 75 against or adjoin the band B, which constitutes in effect a separately formed flange, or continued to form the integral wall or flange B', Fig. 7, and the flange c², to bear against 80 or adjoin the post A. The lowest or discharge floor-plate C', (Fig. 6) is shortened and does not extend to the post A. Its outer flange c', is of the same formation as that of the plates higher up, while 85 its inner flange c², is turned down instead of up, so as to afford and facilitate an easy passage to a storage bin or to a leading-off plate, or to discharge inwardly; and in this case we may omit the outer band as shown 90 by Fig. 8.

In Fig. 1, the spiral chute is shown as connecting with feed-chutes D, and D', which permit the materials to enter at different levels, and after passing down the conveyer, the discharge takes place at the outlet chute 95 E, which is connected in the space between the downturned inner flange c² of the lower floor-plate c', and the post A, as clearly seen in Fig. 6. The outer and inner upturned flanges c', and c², are bent or curved and 100 diverge or flare in opposite directions; the outer one inclines upwardly and is made to bear against the band or wall B, and the inner one is made to bear against the post A, thus forming a hollow space as it were 105 from the top to the bottom of the spiral, which formation of the run-way leads the materials over a practically smooth surface and lowers them with an ease that prevents 110 their becoming chipped or broken to any great extent, if at all, and as a conveyer for use in coal breakers this form of chute may

be made in sizes adapted to different sizes of coal, such as egg, broken, stove, chestnut, pea, etc. It can also be made any height, in sections from ten to sixteen feet, or in such other lengths as may be suited to the prevailing conditions and intended uses.

The outer flange on the floor-plates prevents or helps to reduce wear against the edge of the upright band or wall B; it also prevents or helps to reduce outside leakage of water or dust and it strengthens the floor-plate itself. The inner flange has similar functions, that is, it prevents leakage of water or fine coal dust against the post, strengthens the floor-plate and prevents wear against the post. These flanges practically confine the wear to the floor-plates which lessens the cost of repair parts.

The floor-plates may also be of utility in spiral separators and the term "spiral chutes" is used broadly, so as to include the various utilities to which the invention is applicable.

Having thus described the invention, what

Copies of this patent may be obtained for five cents each, by addressing the "Commissioner of Patents, Washington, D. C."

I claim as new and desire to secure by Letters Patent is:

1. A spiral chute, comprising a central post, helical floor-plates having upturned outer and inner flanges, said floor-plates being secured to said post and bearing at their inner edges against said post to form a runway of which the post is the inner wall, the lower portion of said runway having its inner edge spaced away from the post and having an inner downturned flange. 35

2. A spiral chute, comprising a central post, helical floor-plates having upturned outer and inner flanges, said floor-plates being secured to said post and bearing at their inner edges against said post to form a runway of which the post is the inner wall, the inner portion of the lower end of the runway being cut away and having its inner edge spaced away from the post. 40
